UNITED STATES PATENT OFFICE.

THOMAS W. GREEN, OF PHILADELPHIA, PENNSYLVANIA, ASSIGNOR TO THOMAS WILBRAHAM GREEN ENGINEERING CO., OF PHILADELPHIA, PENNSYLVANIA, A CORPORATION OF PENNSYLVANIA.

SUCTION STREET CLEANER.

Application filed March 1, 1923. Serial No. 622,091.

My invention relates to street cleaners and more particularly to cleaners adapted to automatically and dustlessly gather the dirt from a street when traversing it. It is particularly adapted to use with an auto truck.

The purpose of my invention is to provide a machine of the character indicated that is at once easy and inexpensive to manufacture and well adapted to meet the needs of service.

A further purpose is to provide means for simultaneously using the discharge and suction of a blower adapted to be driven along a street by auto, providing a succession of suction ports with a succession of enveloping and inwardly directed discharge ports, in front and rear as well as at the sides thereof. The blast from the forward discharge ports loosens the dirt and drives it toward the suction ports while the blasts from the side and rearward discharge ports give the street a final scrubbing, driving the dirt forward to the same suction ports.

A further purpose is to provide a novel separator and dirt tank whereby the dirt gathered from the street is continuously separated from the air and is continuously delivered into the dirt tank.

Further purposes will appear in the specification and claims.

I have preferred to illustrate my invention by but one form except with respect to a minor detail, selecting a form which is at once practical and efficient in operation and which well illustrates the principles involved.

Figure 1 is a side elevation of apparatus illustrating my invention.

Figure 2 is a rear elevation of a structure like Figure 1, except that it shows a different form of dirt separator.

Figures 3, 4 and 5 are respectively top plan, and front and side elevations of the dirt-gathering shoe with blast connections from the blower and delivery pipes to the separator.

Figure 6 is a bottom plan view of Figure 3 but with the bottom plate cut away upon one half of the figure.

Figure 7 is a section upon the line 7—7 of Figure 6.

Figure 8 is an enlarged section showing a part of Figure 7.

Figures 9 and 10 are respectively side

elevation and section upon line 10—10 in Figure 9 showing the dirt tank.

Figures 11 and 12 are front and side elevations of one form of dirt-separator, that shown in Figure 2. The covering is partly removed in Figure 12.

Figures 13 and 14 are front and side elevations of another form of separator, that shown in Figure 1.

Figure 15 is a top plan view showing the separator of Figures 13 and 14 in position.

Figure 16 is a fragmentary section of Figure 15 upon line 16—16.

Figure 17 is a fragmentary end elevation of Figure 15, a part being broken away.

In all the figures like numbers refer to like parts.

Describing in illustration and not in limitation and referring to the drawings:

Conditions of service for suction street cleaners are much more severe than those for vacuum cleaners for use upon the floors of houses. In the vacuum cleaners for houses, the dirt-gathering shoes are relatively very small and moreover in use they reciprocate repeatedly back and forth over the surface being cleaned. By reason of the relatively small area of the shoe and the uniform flatness of floors there is little trouble from lack of uniformity of fitting engagement between the shoe and the floor, and by reason of the repeated reciprocation during cleaning, dirt and dust missed during a forward stroke of the cleaner is caught during a return stroke.

In the suction street cleaner the dirt-gathering shoe is relatively very large and inequalities of street surface are such as to make impossible any close uniformity of distance between the shoe and different parts of the street. Moreover, the street cleaner does not reciprocate but must make a clean job of it in one passage, a condition particularly stringent in view of the presence of compacted manure and other refuse clinging to the street, as well as loose and bulky wastes which should be picked up and carried along with a single passage of the cleaner and with a minimum of dust.

In meeting these stringent conditions, I support the suction plate 20 relatively well above the surface of the street, and about its surface downwardly and inwardly direct upon the street through ports 21 a blast of

air sufficiently heavy to blow all ordinary dirt upon the portion 22 of the street beneath the shoe from the street surface at high velocity. The loosened and rapidly moving refuse is caught in suction ports 23, 23' and is carried through suitable conduits 24 into a casing 25.

The same volume of air flows through the suction ports to the dirt reservoir that is used 10 to blow the dirt from the surface of the street, as I connect the intake pipe 26 of the blower 27 to the casing and the outlet 28 of the blower to the pressure blast upon the street surface beneath the shoe.

15 Except for gradual diffusion, the same air is circulated and re-circulated over and over, as the greater part of the same air which leaves the discharge ports spaced around the shoe and strikes the pavement in 20 a heavy blast to loosen and raise the dirt beneath the shoe reenters the shoe loaded with dirt at the suction ports. There is thus no appreciable flow of air away from the shoe on the surface of the street and consequently 25 no tendency to raise dust other than that which is swept through the suction ports to the casing.

The blower for simultaneously affording heavy circulation of air to and from beneath 30 the shoe may obviously be of any type capable of supplying the blast and the Root type blower shown is merely a preferred form. Advantages of this type of blower lie in its 35 adaptation to high suction and pressure with high capacity as well as in its adaptation to reversal in direction of flow. The reversal permits loosening of clogging matter by brief reverse rotation and without requiring opening or handling of the clogged parts.

40 The forward end of the shoe is upwardly sloped as at 29.

The blower 27 is shown as mounted directly back of the seat 30 of the truck chassis 31 and discharges to the shoe through the 45 outlet pipe 28 and flange slip joint 32. Because flow about the pressure chamber 33 is restricted by the connections of pipes 24 the air is distributed through pipe 34 and branches 35 and 36. The blast openings 50 (nozzles) 21 lead directly from the chamber. The pressure chamber is divided from the suction chamber 37 by a diagonal wall 38. The connection of pipes 24 with the suction chamber is by flange slip joints 39.

55 Within the casing 25 the pipes 24 discharge on opposite sides above a dirt-receiving basket or box 40 resting in the bottom of the casing and shown in two different forms. In Figures 9 and 10 this box is 60 mounted upon wheels 41 so as to be free to roll within the bottom of the casing 25 and is provided with a hinged end 42 which may be opened for removal of the dirt with or 65 without removal of the box. In Figure 2 the box 40' is provided similar in location

and use to box 40. The casing is closed by door 42' opposite the box.

The outlet of air withdrawn through pipe 26 to feed the blower is taken within a filter preferably of circular form at 43 and 70 desirably rotated, of which one form is shown in Figures 13-17. The screen may however, be in the form of a fixed casing 44 of any desired shape whose interior is in communication with the pipe 26. In either 75 case the exterior is of filtering material such as canvas and as shown at 45, mounted upon a wire netting support 46.

In the case of the rotary form I have shown it as mounted within the upper part 80 of the casing 25 upon a shaft 47 passing through the casing and driven by a worm 48 and worm gear at 49. One end of the cylindrical screen is closed at 50 and the other end 51 is open and in communication 85 with the end of the pipe 26.

In order that the dust and dirt within the casing may clog the surface and end of the screen as little as possible, brushes 52 and 53 are mounted to bear against these surfaces 90 and to scrape them as the screen rotates.

Rotation of the screen is provided by pulley 54 upon a blower shaft connecting with pulley 55 whose shaft carries worm 48. The 95 pulleys are connected by belt 56.

The blower is driven as by belt 57 from any part of the connecting mechanism between the engine 58 and the driving wheels (front or back) or connected with any of them. It has not been considered necessary 100 to show the detail of any of this driving mechanism.

The shoe 20 is resiliently supported by any suitable means such as four cylinders 59 secured to the frame 31 and rods 60 secured to 105 the shoe and terminating in heads 61 resting on spiral compression springs 62 within the cylinders.

The form of the shoe is permissibly varied considerably, though preferably I give it the 110 general form of a diamond having rounded apices, as best seen in Figures 3 and 6. The discharge ports 21 are preferably arranged so that there is a discharge port about half way between each pair of successive suction 115 ports.

The shoe may be made up of pressed metal parts so arranged as to form chambers in the form of a divided annulus—or two annuli of generally triangular form in cross section—120 having the suction chamber inside and below the pressure chamber to present full suction ports in a flat lower surface. The pressure annulus in that case lies outside of and above the suction annulus, and presents an 125 edge only at the bottom within which are formed the blast ports.

In the construction of the shoe the suction chamber 37 is formed between the bottom plate 63 and the walls 64 and 38 forming an 130

annulus of triangular section. As illustrated in section the wall 38 forms the hypotenuse of a right triangle of which wall 64 forms a side. Both edges of the annulus 5 are rigidly secured to the bottom plate.

As has been explained the partition wall 38 serves as one wall also of a compartment 33, forming in section the hypotenuse of a second right triangle whose opposite sides 10 66 and 67 are formed from the top plate 65. The top plate is rigidly secured to side 38 or 64 or to both of them. I show rivets or without angles at the joints as a common means for fastening these plates together.

15 In order that the interior of the upper part of the casing may be accessible without releasing the bearing for the rotary air filter and without necessity for full bearing support when the doors are open, the rear 20 end of the shaft 47 is supported by a bearing 69 hung by means of any bracket or strap 70 and extending at the back so as to be supported by the doors when they are closed. The upper doors divide along a 25 vertical medial line and each door carries a half, 72 of a support for the bearing 69 inclosing between them the extension 73. This gives the strap and bearing additional support when the doors are closed and makes it 30 possible to use a light strap which is little in the way. It may even be flexible.

The brush 52 is shown as supported by the bracket or strap. It may be given stiffness in directions parallel with the shaft 47 35 by the pressure of the doors against it.

Where the non-rotatable form of separator or air filter is used as in Figure 2, I support it by flanges 74 sliding in angles or other supports 75 so that the open end 76 40 is in contact with the casing end about pipe 26.

A rake 77 shown diagrammatically, is provided in front of the shoe. This rake serves the double purpose of fending off material 45 too large for the shoe, such as boxes and boards, and of so scattering and spreading out horse droppings and small heaps of refuse dumped upon the street, as to permit the shoe to gather them up clean.

50 While I have described my invention in connection with the street cleaning use for which it has undoubtedly utility, I recognize that on a smaller scale it will be highly advantageous for use in cleaning large surfaces indoors, particularly in stores and other such public places where the present cleaners are but poorly suited because of the excessive amount of dirt and the large areas to be covered. It is my intention therefore to 55 apply my invention to both of these uses.

In operation the cleaner is moved along the street or floor area at the same time that the blower 27 is operated to direct a blast 60 of air about the edges of the shoe. Coincidentally with this blast the suction of air

from the casing through pipe 26 tends to produce a vacuum within the casing, applying the suction to the inlet (suction) openings 23, 23' and resulting in these suction openings gathering in substantially all of 70 the air which has been driven down against the surface, along with the dust or dirt which have been loosened by the blast.

As the dirt-laden air reaches the interior 75 of the casing the dust and dirt fall into the storage box. Any tendency of the dust and dirt in the air within the casing to be delivered upon or to settle upon the surface of the separator and to clog this surface is corrected in the rotary form by scraping 80 the surface as it rotates. Where the rotary form of separator is not used a blast driven through the pipes backward by reversing the direction of rotation of the parts causes any dirt which has attached itself to the surface 85 of the separator to be cast off.

The freedom of the shoe to lift at either end and at either side allows it to follow somewhat the contour of the street or irregularities in the floor, sliding over humps and 90 accommodating easily to slopes of the surface.

The door 42' when open forms a platform or slope upon which the refuse box or car can be withdrawn and by which it can be 95 conveniently replaced.

In view of my disclosure those familiar with the art will see various other ways in which all or part of the advantage of my invention may be secured and it is my purpose 100 therefore to cover herein all such changes and modifications as come within the reasonable spirit and scope of my claims.

Having thus described my invention, what I claim as new and desire to secure by Letters Patent is:

1. In a dirt gathering device, a shoe having small downwardly directed suction ports arranged about the periphery of the bottom of the shoe and closed in the space 110 between the ports means for moving the shoe over a surface to be cleaned and means for producing an air-blast upon the surface about all of the suction ports and angularly inclined theretoward.

2. In a dirt gathering device, a wheeled support, a blower near the forward end thereof, a dirt gathering shoe having downwardly directed suction ports and pressure outlets, the latter surrounding the space 120 into which the suction ports open, the surface of the shoe being closed in the space between the ports, resilient connections between the support and the shoe maintaining the shoe somewhat above and substantially 125 parallel with the surface, a conduit connection between the discharge side of the blower and the outlets, a dirt receiving chamber on the support, another flexible conduit connection between the chamber and the 130

suction ports, and a conduit connection from the chamber to the inlet of the blower.

3. A dirt gathering device, comprising a wheel mounted frame, a shoe carried thereby, a casing upon the frame, a blower, and downwardly opening pressure and exhaust connections from the blower with said shoe leading from and exhausting into said casing and having the pressure ports located 10 outside of the exhaust ports, the surface within and between the exhaust ports being closed.

4. A dirt gathering device, comprising a wheel mounted frame, a shoe carried thereby, a casing upon the frame, a blower and pressure and exhaust connections from said blower with said shoe leading from and exhausting into said casing and having the pressure ports located between exhaust ports.

5. In a dirt gathering device, a wheel mounted frame, a shoe carried thereby hav-

ing a bottom closed throughout the greater part of its extent, a blower carried by the frame, connections between the blower and shoe discharging through openings spaced 25 about the outer circumference of the shoe and suction connections with said shoe leading from suction ports located inside the pressure ports and in close proximity to them and connected to discharge into said 30 casing.

6. A shoe for blast and suction surface cleaning comprising a pressure annulus and a suction annulus, the pressure annulus being ported about its outer circumference and 35 the suction annulus being ported along the bottom and closed between the ports in combination with pressure and suction connections to the two annuli and common blower mechanism for creating the pressure and 40 suction.

THOMAS W. GREEN.
